UNITED STATES PATENT OFFICE

91,636

DESIGN FOR AN ILLUMINATED MAKE-UP MIRROR

Raymond Ring, William L. Pereira, and James
Horsley, Chicago, Ill.; said Pereira and said
Horsley assignors to said Ring

Application December 20, 1933, Serial No. 50,150

Term of patent 14 years

To all whom it may concern:

Be it known that we, RAYMOND RING, WILLIAM
PEREIRA and JAMES HORSLEY, citizens of the United
States, residing at Chicago, in the county of Cook
and State of Illinois, have invented a new, orig-
inal, and ornamental Design for an Illuminated
Make-Up Mirror, of which the following is a
specification, reference being had to the accom-
panying drawing forming a part thereof, in
which—

Figure 1 is a side view;
Fig. 2 is a front view;
Fig. 3 is a rear view.

We claim:

The ornamental design for an illuminated
make-up mirror, as shown.

RAYMOND RING.
WILLIAM L. PEREIRA.
JAMES HORSLEY.
